APPARATUS FOR FORMING MOLDS

Howard Emery and Andrew Irvine, Detroit,
Mich., assignors to Bohn Aluminum & Brass
Corporation, Detroit, Mich., a corporation of
Michigan

Application February 29, 1932. Serial No. 595,898

14 Claims. (Cl. 22—103)

This invention relates generally to molds and refers more particularly to an improved apparatus for forming molds.

Although the present invention may be employed with facility in the manufacture of various articles, nevertheless, it finds particular use when employed in fashioning cylinder heads for multi-cylinder internal combustion engines wherein it is desirable to form each of the combustion chambers of accurate predetermined size and in addition to form the walls of these chambers of uniform density.

The present invention contemplates the provision of a mold which insures securing the foregoing advantageous features by employing permanent cores or metallic chills for forming the portions of the mold cavity defining the combustion chambers and by insuring accurate location of these chills within one of the mold sections.

One of the principal objects of this invention resides in the novel means provided herein for accurately locating the chills in a mold box prior to ramming the molding material within the latter so that upon completion of this section of the mold, the portions of the chills corresponding to the dimension of the combustion chambers will project beyond one surface of the molding material accurate predetermined distances.

A further advantageous feature of the present invention which contributes materially to simplifying and expediting production is attributed to those steps in the method of fashioning the molds which consist in removing the flasks from the molds immediately after the ramming operation and subjecting the molds to a baking process which, in addition to increasing the efficiency of the resultant castings, also permits handling the molds throughout the subsequent operations without the supporting assistance of the flasks. By virtue of the foregoing arrangement, the flasks are employed only during the time the mold is being rammed, with the result that a relatively small number of flasks are capable of producing a comparatively large number of molds.

In instances where the flasks are removed as specified above and the mold is formed of cope and drag sections, it is highly desirable to provide some means independent of the flasks for accurately locating the cope and drag sections relative to each other prior to the pouring operation, and, accordingly, another object of this invention resides in the novel manner in which the foregoing function is accomplished herein.

The foregoing as well as other objects will be made more apparent as this description proceeds, especially when considered in connection with the accompanying drawings, wherein:

Figure 1 is a longitudinal sectional view through a mold forming the subject matter of the present invention;

Figure 2 is a cross sectional view taken substantially on the line 2—2 of Figure 1;

Figure 3 is a fragmentary sectional view illustrating the cope section of the molding apparatus;

Figure 4 is a plan view of the drag flask prior to compacting the molding material therein;

Figure 5 is a cross sectional view taken on the line 5—5 of Figure 4;

Figure 6 is a sectional view taken on the line 6—6 of Figure 4;

Figure 7 is a fragmentary sectional view illustrating the manner in which the cope and drag sections of the mold are accurately located with respect to each other; and

Figure 8 is a fragmentary sectional view taken substantially on the line 8—8 of Figure 4.

Referring now to the drawings, it will be noted that we have illustrated in Figure 1 a mold 10 comprising a cope section 11 and a drag section 12. Embedded within the upper surface of the drag section in predetermined spaced relation to each other is a plurality of chills 13 having portions projecting predetermined distances above the upper face of the drag section and cooperating with the dry sand core 14 in the cope section of the mold to form the portions of the mold cavity defining the combustion chambers. The members 13 are accurately machined to conform to the contour of the desired combustion chambers and are preferably formed of metal so as to chill the walls of the combustion chambers and thereby increase the density of these walls.

In casting cylinder heads, it is also highly desirable to chill or increase the density of the portions of the casting to be subsequently drilled for receiving the stud bolts and for accomplishing this result, a plurality of additional chills 15 are embedded within the drag opposite the aforesaid portions of the casting and flush with the top surface of the drag. Cooperating with the chills 15 to perform the above function is a plurality of risers 16 formed within the cope section of the mold and fashioned to supply the maximum amount of metal to the portions of the casting to be subsequently drilled for the stud bolts.

In the method of fashioning the mold, the

cope and drag sections are formed by compacting the molding material within suitable flasks by ramming apparatus, not shown herein, but which may be any one of a number of the well known designs. After the cope and drag sections of the mold have been completely formed in their respective flasks, the latter are removed and the aforesaid sections are thoroughly baked permitting subsequent handling of the same without the assistance of the flasks. The foregoing construction materially simplifies and expedites handling of the mold sections as well as reduces the cost of manufacture since a relatively few number of flasks are capable of producing a comparatively great number of molds in rapid succession.

In view of the fact that the flasks are removed from the mold sections immediately after forming the same, it is desirable to provide some means for accurately locating the cope and drag sections of the mold with respect to each other prior to the pouring operation. This is accomplished in providing a pair of pins 17 having cylindrical intermediate portions 18 and having oppositely tapered end portions 19 and 20. The lower tapered ends 19 of the pins are fashioned to engage within correspondingly tapered openings formed in opposite ends of the drag section during the ramming operation while the upper ends of the pins project above the top surface of the latter section for engaging within suitable annular washers 21 embedded within the cope section flush with the bottom surface of the latter. The internal diameter of the washers is so determined with respect to the external diameter of the intermediate portions 18 of the pins as to snugly engage the latter and thereby prevent relative shifting of the cope and drag sections. After the cope and drag sections of the mold have been properly positioned in the manner outlined above, the pins are preferably removed from the mold by means of a suitable tool 22 insertable within the openings 19 in the cope and threaded for engagement with tapped openings in the upper ends of the pins.

Inasmuch as the operation of an internal combustion engine is materially affected by variations in volume of the various cylinders of the engine, it is highly desirable to uniformly fashion each of the combustion chambers to accurate predetermined dimensions and in order to accomplish this result without resorting to the costly method of machining the combustion chamber walls, it is necessary to accurately predetermined the location of the chills 13 in the drag section of the mold. The foregoing is accomplished herein by providing the drag mold flask 24 with a metallic plate 25 secured to the inner surface of the bottom wall 26 of the flask and formed with a plurality of openings 27 therethrough corresponding in number to the number of chills 13 employed in the mold. The openings 27 are spaced from each other predetermined distances accurately conforming to the spacing of the combustion chambers in the cylinder head and the dimension of these openings is such as to permit the portion of the chills 13 forming the inner walls of the combustion chambers to extend downwardly through the openings 27 into suitable recesses 28 formed in the bottom wall 26 of the flask. While from the previous description it will be observed that the openings 27 in the plate 25 serve to accurately space the chills 13 relative to each other, nevertheless, some means must be provided for sup-

porting the chills in the aforesaid openings so that the portions of the chills extending below the plate 25 conform exactly to the desired dimension of the combustion chambers to be ultimately formed. In the present instance, each of the chills are provided with marginal flanges 23 forming continuations of the bottom surfaces thereof and fashioned to overlap the inner surfaces of the marginal edges of the openings 27 as clearly shown in Figure 5. Inasmuch as the pressures subjected to the molding material in the flask 24 by the ramming apparatus are transferred directly to the chills 13, there is a tendency for the latter to sag, and since sagging of the chills during the ramming operation materially affects the accuracy of the resulting combustion chambers, it is highly desirable to provide some means for eliminating any such tendency. This is accomplished herein by providing additional supporting means for the chills 13 in the form of a plurality of sets of pins for each chill. While the number of pins in each set may vary as desired, nevertheless, we prefer, in the present instance, to employ three pins in each set suitably spaced from each other to provide a three-point support for each chill. These pins are designated in Figure 4 of the drawings by the reference characters 30, 31 and 32 and project upwardly into the recesses 28 from a plate 33 secured to the underside of the flask. As shown in Figure 5 of the drawings, the pins are provided with reduced portions at the lower ends thereof extending through suitable openings formed in the plate 33 and forming shoulders 34 engageable with the upper surface of the plate 33 for determining the length of the pins projecting above the plate. Owing to the irregular contour of the chills 13, the length of the portion of each pin projecting upwardly from the plate 33 may vary in accordance with the portion of the chill engaged thereby, but in each instance the aforesaid length is predetermined so that the pins cooperate with the plate 25 to support the chills. The spacing of the openings in the plate 33 through which the reduced ends of the pins project determines the spacing of the latter and the same are rigidly secured to the plate 33 by nuts 35 threaded upon the ends of the pins. In this connection, it is to be understood that suitable shims are provided on the pins between the shoulders 34 and plate 33 so as to permit varying the length of the pins projecting above the openings by either removing or inserting additional shims depending upon the adjustment desired.

In order to provide for checking the cylinder head casting to determine whether the same has warped in the mold, each of the chills 13 is formed with a depression 38 having flat walls 39 arranged to engage the pin 30 of each set when the chills 13 are located in the drag flask. The pins 30 are fashioned to locate the flat surfaces in a common plane substantially parallel to the plane in which the chills are supported by the remaining pins and marginal flanges 23 on the chills. By reason of the foregoing arrangement, it will be seen that the depressions 38 form bosses on the cylinder head casting having flat walls corresponding to the walls 39 of the depressions. If the casting has been properly formed in the mold the flat wall portions of the bosses will also lie in a common plane, but, if for one reason or another the casting warps during the molding process, the latter flat portions will be correspondingly displaced. The

condition of the casting may be readily calculated by selecting one of the flat wall portions of the bosses and determining the positions of the remaining wall portions relative thereto.

- 5 The plate 25, in addition to locating the chills 13 with respect to each other, also forms a support for the chills 15 and for the tapered pins 38'. As shown in Figure 4 of the drawings, the front and rear rows of chills 15 are accurately positioned upon the plate 25 by means of pins 39' projecting upwardly from the aforesaid plate at predetermined points and engageable with suitable recesses formed in the base portions of the chills 15. While the center row of chills 15 may be 15 similarly positioned, if desired, nevertheless, it is found that in actual practice, these chills may be located with sufficient accuracy by the combustion chamber chills 13, and, accordingly, we have illustrated the former chills as being so positioned.

20 The tapered pins 38' serve to form the tapered openings in opposite ends of the drag section for receiving the tapered portions 19 of the pins 18 in the manner and for the purpose hereinbefore set forth. The lower ends of the pins 38' are provided with reduced portions 40 extending through suitable openings formed in the bottom of the drag flask and threaded as at 25 41 for attachment to the bottom plate 33 of said flask. The reduced portions aforesaid of the pins form annular shoulders 42 on the latter of greater diameter than the openings through which the reduced ends aforesaid of the pins extend so as to engage the chill supporting plate 33 and thereby cooperate with the threaded connection between the pins and plate 33 to permanently secure the pins in place.

In the method of forming the drag section of the mold, the chills 13 and 15 are accurately positioned upon the inner wall 25 of the drag mold flask 24 in the manner previously described, and molding material is compacted within the flask by any suitable apparatus. Upon completion of the ramming operation, a suitable plate 50 is placed upon the top of the drag flask and the latter is inverted to position the chills uppermost. The flask 24, together with the pins 38', is then removed and the mold section introduced to a baking process. After the latter process, the pins 18 are inserted within the openings in the drag section of the mold provided by the pins 38' and the core 14 is positioned in the usual manner on the drag section.

The cope section of the mold is preferably fashioned simultaneously with the drag section and is formed in accordance with the usual practice with a mold cavity therein cooperating with the core 14 to form the outer walls of the casting. A plurality of riser openings are also formed in the cope section during the ramming operation for the purpose specified above and additional openings are formed in opposite ends thereof for receiving the upper ends of the pins 18. The latter openings are produced by tapered pins 51 projecting upwardly from the bottom of the cope flask and fashioned to support the washers 21 in a position so determined that the latter will be embedded in the molding material flush with the top surface of the cope section.

70 The cope section of the mold is also baked subsequent to the ramming operation in the same manner as the drag section and upon completion of the baking process is placed upon the top of the drag, as clearly shown in Figure 1, with the

tapered upper ends of the pins 18 extending into the openings in the cope, formed by the pins 51, through the washers 21. The pins 18 are then removed by the tool 22 and the molten metal poured into the mold through suitable spaces 80 provided for this purpose. After the mold has been poured as stated above, the same is permitted to cool whereupon it is broken up and the resulting casting suitably machined.

What we claim as our invention is:

1. Apparatus for forming a mold section having a metal chill member, comprising a flask fashioned to receive molding material and having a bottom wall provided with a recess therein for receiving a portion of said metal chill member, and means carried by said bottom wall for engaging the portion aforesaid of said chill for supporting the same in predetermined relation to said bottom wall. 90

2. Apparatus for forming a mold section having a metal chill member, comprising a flask fashioned to receive molding material and having a bottom wall provided with a recess therein for receiving a portion of said metal chill member, means for supporting the metal chill member in 100 the flask with the portion aforesaid thereof in predetermined relation to the bottom wall of the flask including a lateral flange on said chill member fashioned to overlap the marginal edge portions of said recess, and a member carried 105 by the bottom wall of said flask and engageable with the portion of said chill extending into the recess to form an additional support for said chill.

3. Apparatus for forming a mold section having a metal chill member, comprising a flask fashioned to receive molding material and having a bottom wall provided with a recess therein for receiving a portion of said metal chill member, and means for supporting the metal chill member in the flask with the portion aforesaid thereof in predetermined relation to the bottom wall of the flask including a plurality of members carried by said flask and engagable with the chill at spaced points. 110

4. Apparatus for forming a mold section having a metal chill member, comprising a flask fashioned to receive molding material and having a bottom wall provided with an opening therethrough for receiving a portion of said chill member, a closure member extending across the lower end of said opening, and means for supporting the metal chill member in the flask with the portion aforesaid thereof in predetermined relation to the inner surface of the bottom wall of 125 the flask including a member extending upwardly from said closure member and engageable with the adjacent face of the chill member.

5. Apparatus for forming a mold section having a metal chill member, comprising a flask fashioned to receive molding material and having a bottom wall provided with an opening therethrough for receiving a portion of said chill member, a closure member extending across the lower end of said opening, and a plurality of 130 members extending upwardly predetermined distances from the closure member into the recess for engaging the adjacent face of the chill at laterally spaced points to support the latter in the flask with the portions aforesaid thereof in 140 accurate predetermined relation to the inner surface of the flask.

6. Apparatus for forming a mold section having a metal chill member, comprising a flask fashioned to receive molding material and hav- 145

ing a bottom wall provided with a recess therein for receiving a portion of said metal chill member, means for supporting the metal chill member in the flask with the portion aforesaid thereof in predetermined relation to the inner surface of the flask including a marginal flange projecting laterally from the chill and fashioned to overlap the inner surfaces of the marginal edges of said recess, and means located within said recess below the chill and engageable with the adjacent face of the latter for cooperating with said flange in accurately supporting said chill relative to the bottom wall of the flask.

7. Apparatus for forming a mold section having a metal chill member, comprising a flask fashioned to receive molding material and having a bottom wall provided with an opening therethrough for receiving a portion of said chill member, a closure member extending across the lower end of said opening, and means for supporting the metal chill member in the flask with the portion aforesaid thereof in predetermined relation to the inner surface of the bottom wall of the flask including a marginal flange projecting laterally from said chill in overlapping relation with the inner surfaces of the bottom wall of the flask surrounding said opening and a member secured to said closure within said recess for engaging the adjacent face of the chill.

8. Apparatus for forming a mold section having a metal chill member, comprising a flask fashioned to receive molding material and having a bottom wall provided with an opening therethrough for receiving a portion of said chill member, a closure member extending across the lower end of said opening, and means for supporting the metal chill member in the flask with the portion aforesaid thereof in predetermined relation to the inner surface of the bottom wall of the flask including a plurality of adjustable pins extending upwardly from the closure member into said recess for engaging the adjacent face of the chill at spaced points.

9. Apparatus for forming a mold section having a plurality of metal chill members, comprising a flask fashioned to receive molding material and having a bottom wall provided with a plurality of spaced recesses therein for receiving portions of a corresponding number of chills, means for accurately locating said chills with respect to each other, and means carried by the flask and extending into said recesses for engaging the chills to accurately support the latter within the flask in predetermined relation to said bottom wall.

10. Apparatus for forming a mold section having a plurality of metal chill members comprising a flask fashioned to receive molding material and having a bottom wall provided with a plurality of spaced recesses therein for receiving portions of a corresponding number of chills, means for accurately locating said chills with respect to each other comprising a plate secured to the inner surface of the bottom wall of said flask and having openings therethrough registering with the recesses of such dimension as to

accurately receive the portions aforesaid of the chills, and means carried by the flask and extending into said recesses for engaging the chills to accurately support the latter within the flask in predetermined relation to said plate.

11. Apparatus for forming a mold section having a plurality of metal chill members comprising a flask fashioned to receive molding material and having a bottom wall provided with a plurality of spaced recesses therein for receiving portions of a corresponding number of chills, means for accurately locating said chills with respect to each other comprising a plate secured to the inner surface of the bottom wall of said flask and having openings therethrough registering with the recesses of such dimension as to accurately receive the portions aforesaid of the chills, means for supporting the metal chill members in the flask with the portions aforesaid thereof in predetermined relation to the inner surface of said plate including marginal flanges projecting laterally from said chills and fashioned to overlap the inner surfaces of the plate surrounding the openings therethrough, and means located within each of said recesses below the portions of the chills therein and engageable with the adjacent faces of the latter for cooperating with said flanges in accurately supporting the chills relative to said plate.

12. Apparatus for forming a mold section having a metal chill member, comprising a flask fashioned to receive molding material and having a bottom wall apertured to receive a portion of the chill member, and means for accurately supporting the chill member in predetermined relation to the inner surface of said bottom wall.

13. Apparatus for forming a mold section having a metal chill member supported upon one surface of the section with a portion of predetermined dimension thereof projecting beyond said surface, comprising a flask fashioned to receive molding material and having a bottom wall apertured to receive the portion aforesaid of the chill member extending beyond the surface aforesaid of the mold section, and means other than said wall for supporting the chill in accurate predetermined relationship to the inner surface of the wall during the formation of said mold section.

14. Apparatus for forming a mold section having a plurality of spaced chill members supported on one surface thereof with portions of the chills extending predetermined distances beyond said surface, comprising a flask fashioned to receive molding material and having a bottom wall apertured to receive the projecting portions of the chill members, means for accurately locating the chill members with respect to each other, and means for supporting the chill members with the projecting portions in accurate predetermined relation to the inner surface of said wall during the formation of the mold section.
